UNITED STATES PATENT OFFICE.

JOSEF B. DECKER, OF ELKTON, MARYLAND.

FIRECRACKER MACHINE.

Application filed June 21, 1927. Serial No. 200,467.

This invention relates to a machine for making firecrackers of the type shown in United States patent to Hitt No. 1,253,596, January 15, 1918, which comprises a tube of paper or the like having mounted therein intermediate its ends a bag containing explosive material.

The object of the invention is to provide a machine which will produce firecrackers of this kind rapidly and economically and eliminate the use of hand operations. A further object is to provide a machine capable of automatically forming the tubes for firecrackers of this kind and forcing the bags of explosive material into the tubes after they are produced. A still further object is to provide a machine having an endless carrier to which the bags of explosive material are supplied and from which they are forced into a magazine and from the magazine into the tubes which are produced in the machine. A still further object is to provide a machine of this kind comprising a magazine for receiving a bag of explosive material together with means for holding a tube adjacent the end of the magazine and for forcing the bag from the magazine into the tube. A still further object is to provide a machine of this kind having a spindle which is adapted to receive a sheet of paper cut from a strip, deliver the same to a spindle and roll the same into the form of a tube, and also having a magazine associated with the spindle for receiving a bag of explosive material together with means for forcing the bag from the magazine into the tube as the spindle is withdrawn from the tube.

The invention further contemplates various novel details of construction in a machine of this type by which the complete firecrackers can be rapidly produced without the necessity of any manual operations.

Still other objects and advantages of the invention will be evident from the nature of the construction which is illustrated in the accompanying drawings and described in the following specification, it being understood that the particular embodiment of the invention illustrated in the drawings may be varied in numerous respects within the spirit of the invention.

In the accompanying drawings:

Figure 1 is a plan view of the complete machine;

Figure 2 is a side elevation of the same;

Figure 3 is a transverse sectional view substantially on the line 3—3 of Fig. 1;

Figure 4 is an enlarged transverse sectional view substantially on the line 4—4 of Fig. 1;

Figure 5 is a longitudinal sectional view substantially on the line 5—5 of Fig. 6, certain parts being omitted for the sake of clearness;

Figure 6 is a plan view of the parts of the machine shown in Fig. 5 and other parts associated therewith;

Figure 7 is a longitudinal sectional view substantially on the line 7—7 of Fig. 1;

Figure 8 is a transverse sectional view substantially on the line 8—8 of Fig. 1;

Figure 9 is a sectional view substantially on the line 9—9 of Fig. 1;

Figure 10 is a detailed sectional view of the means for intermittently operating the paper feed rolls shown particularly in Fig. 7;

Figure 11 is a side elevation of the parts shown in Fig. 10;

Figure 12 is an enlarged fragmentary side elevation showing the construction of the endless carrier;

Figure 13 is a detailed sectional view showing the construction of the spindle for rolling the tubes and part of the adjacent tilting platform for supplying the paper blanks to the spindle;

Figure 14 is an enlarged detailed sectional view showing the spring pressed clamping pad for holding the paper blanks on the tilting platform;

Figure 15 is a perspective view of the completed article formed by the machine; and

Figure 16 is a perspective view of the parts of the article before the bag is inserted in the tube.

Referring to the drawings in detail, the numeral 10 indicates any suitable table or support upon which the parts of the machine are mounted and which is preferably supported by suitable standards 10^a. The main drive shaft 11 of the machine is suitably journaled on the table 10 and extends transversely thereof adjacent one end. This shaft is rotated by a pulley 11^a attached thereto which is driven by means of a belt (not shown), the belt being shiftable to the idle pulley 11^b by means of the belt shifter 11^c.

Connected to the shaft 11 by beveled gear-

ing 12 is the shaft 13 which extends longitudinally of the table 10 and is suitably journaled in bearings mounted thereon. Another set of beveled gearing 12^a serves to 5 connect the shaft 11 to a second shaft 15 also journaled on the table 10 and extending longitudinally thereof on the opposite side from the shaft 13. The shafts 11, 13 and 15 rotate constantly during operation 10 of the machine.

In general, the machine includes means for 15 feeding paper in a continuous strip, means for cutting the paper into sheets and feeding the sheets to a spindle, means for wrapping the sheets about the spindle to form the tubes, and means for inserting the bags of explosive material into the formed tubes. For the sake of clearness, these various parts 20 of the machine will be described more or less separately.

The paper feeding and cutting mechanism.

The paper is preferably supplied to the machine from a continuous strip and paste 25 or glue is applied to one side thereof, but as this part of the mechanism is immaterial to the present invention, no detailed description of the same is necessary. It is sufficient to note that the shaft 13 on its end opposite the shaft 11 is provided with a beveled gear 14 which cooperates with a corresponding gear 14^a on a transverse shaft 14^b carrying a roller 14^c on which rests an idle roller 14^d journaled in the brackets 14^e. The shaft 14^b 30 is connected by suitable gearing 16 to a second transverse shaft 17, the latter being provided with a roll 18 which extends downwardly into a glue pan P. The roll 18 serves to apply glue to one side of the paper which 35 is led into contact therewith from a supply roll (not shown). After being thus supplied with glue, the paper is led over certain idle rolls (not shown) and is then caused to pass between the rolls 14^c, 14^d and into the machine. 40

In passing into the machine, the paper is led between the cooperating rolls 19 and 20 which are journaled in suitable standards 21 on the table 10. The rolls 19 and 20 are rotated intermittently and constitute measuring feed rolls, or in other words, these rolls at each operation serve to feed a measured amount of the paper into the machine. The rolls 19 and 20 are provided with suitable shafts which are received in slots 21^a 45 of the standards 21, the upper roll 19 resting by gravity on the lower roll 20. The ends of the rolls 19 and 20 or the shafts of the same, are provided respectively with gears 19^a, 20^a meshing with each other, the gear 20^a meshing with a pinion 22 rotatable on a stub shaft 22^a secured in the standard 21 and rigid with a large gear wheel 22^b 60 which is driven from a pinion 23 rigidly secured to a beveled gear 24 which in turn is

rotated from the mutilated beveled gear wheel 25 secured to the shaft 13. The beveled gear wheel 25 is rotated continuously but the connection between this gear and the rolls 19 and 20 is such that the rolls are 70 given an intermittent rotation. The gear 25 has beveled teeth 25^a on a part only of its periphery, as illustrated particularly in Figure 11. Outside of the gear teeth 25^a the gear wheel is provided with a flat surface 75 25^b. A member 26 is arranged between and rigidly associated with the gears 23 and 24 and is formed with a flat surface 26^a. This flat surface cooperates with the flat surface 26^a formed on the member 26. The flat surface 25^b of the gear wheel 25 is provided with a depressed portion 25^c as illustrated 80 particularly in Figure 11. From this it will be understood that as the gear wheel 25 rotates, the cooperating gears 24 and 23 and 85 the rolls 19 and 20 will be driven so long as the gear teeth 25^a on the wheel 25 are in mesh with the teeth on the gear wheel 24. When the wheel 25 rotates to the extent that the teeth 25^a are no longer in mesh with the teeth on the gear 24, the member 26 will have been rotated to a sufficient extent that the flat surface 26^a thereof will come in contact with the flat surface 25^b on the gear wheel 25. This serves to lock the pinion 90 and gear 23, 24 and consequently the rolls 19 and 20 against further rotation until the gear wheel 25 has rotated a sufficient degree to again bring the teeth 25^a thereof into engagement with the beveled gear 24 whereupon this gear together with the rolls 19 and 20 will again be rotated. 100

It will be understood that the intermittent rotation of the rolls 19 and 20 thus produced is sufficient at each operation to feed 105 the desired amount of paper into the machine.

Cooperating with the feed rolls 19 and 20 are longitudinal guides between which the paper is caused to pass. These guides include a plurality of upper strips 30 which are secured at one end to a cross bar 31 and at the other end to a cross bar 32, the former being supported in the standards 21 and the latter being arranged to rest on lower guide 110 strips 33 which are also secured together by means of a cross bar 34 also supported in any suitable manner on the standards 21. The paper passes between the guide strips 30 and 33 and beneath the cross bar 32. 115

As the paper is thus fed intermittently to the machine, it is cut into short pieces or strips of a length corresponding to the length of the tubes to be formed. Such cutting operation is performed by means of a 120 movable cutter 35 extending transversely of the machine and cooperating with a stationary cutter 36 over which the paper is adapted to pass. The cutter 35 is pivoted at 125 37 intermediate its length to a bracket on the 130

table 10 and the same is intermittently operated by means of a cam 38 mounted on the shaft 13, the cutter being provided with a roller 35^a which is held in constant engagement with the cam 38 by means of a coiled spring 39. This spring serves to hold the cutter 35 elevated except when the cam 38 comes into operation to move the same downwardly to sever the paper. The spring 39 is arranged so as to exert somewhat of a lateral pull against the cutter 35 which serves to hold the edge of the cutter 35 at all times against the stationary cutter 36.

The sheets of paper or tube blanks cut from the strip are received upon a tilting and laterally movable platform 40 pivotally supported at one end on a standard 41, the other end of this platform being pivotally connected to a lever 42 which is also pivoted intermediate its length on the standard 41. The free end of the lever 42 is arranged adjacent the shaft 13 and is provided with a roller adapted to bear against a cam 43 secured to said shaft. A coiled spring 44 is also connected to the lever 42 and normally exerts a downward pressure upon the end of the same opposite the cam 43. From the foregoing it will be seen that as the shaft 13 rotates the lever 42 will be operated so as to hold the tilting platform 40 in a substantially horizontal position as a sheet or blank cut from the strip is deposited thereon, after which the platform will be tilted into the position shown particularly in Figure 3. The

platform 40 not only has a tilting movement but has a slight bodily movement up and down and also a slight lateral movement as it is tilted downwardly. To effect this result, the upper end of the standard 41 has a diagonal slot 41^a formed therein and the platform 40 on its under side has a projection 40^a carrying a pin 40^b which slidably engages in the slot 41^a of the standard. When the platform 40 is raised into horizontal position by the lever 42, the pin 40^b will slide up the inclined slot 41^a so that the platform will be positioned close to the lower cutter 36 to receive the sheet or blank severed from the strip. The paper strip is fed into the machine so that the sheet or blank cut therefrom will extend a slight distance beyond or project over the lower or left-hand end of the platform. This is shown particularly in Figure 13 of the drawing. After a sheet or blank has been deposited on the platform 40 and as the same is moved downwardly, it will also be moved toward the left in Figure 3 so that the projecting edge of the blank will be placed in position to be engaged by the tube winding mechanism.

In order to hold the sheet or blank on the platform 40 while the latter is being moved downwardly and laterally, means are provided for clamping the same against the

platform 40. This means comprises a lever 45 also pivoted intermediate its length at 45^a to the standard 41. The lever 45 adjacent the platform 40 is provided with a laterally extending arm 45^b which carries a clamping member or pad 46 movably secured thereto by means of a bolt 47 and guide pins 48. The pad 46 is made yieldable by means of springs 49 interposed between the same and the arm 45^b of the lever. The rear end of the lever 45 extends to a point adjacent the shaft 13 and is provided with a roller 50 adapted to bear against a cam 51 on said shaft, the roller being held against the cam by means of a coiled spring 52 anchored to the lever and to the table 10. As the shaft 13 is rotated it will be understood that the cam 51 tilts the lever 45 to move the pad 46 downwardly toward the platform 40 and thereby clamp the sheet on the platform. The parts are so timed that when the platform 40 is raised to receive a blank cut from the strip, the pad 46 will be in position above the platform. Just before the blank is severed the clamp or pad 46 is caused to move against the platform and thus hold the paper while the blank is cut and while the platform is moved downwardly and laterally as above described. After the blank is engaged by the spindle 56, the clamp or pad 46 is again moved upwardly so that the blank is free to move into the tube forming mechanism.

The tube winding mechanism.

100

A tube winding shaft 55 extends longitudinally of the table 10 and is supported in suitable standards 55^a. The shaft 55 at its free end terminates in or has secured thereto a hollow spindle 56 which is provided with a longitudinal slot 56^a which is adapted to engage the forward projecting end of the sheet or blank on the tilting platform 40. After the sheet is engaged by the spindle 56, the latter is rotated to wind the sheet a number of times around the spindle whereby the tube is formed.

The rotation of the spindle shaft 55 is intermittent and is derived from the shaft 15 through any suitable intermittent gearing. That shown comprises a mutilated gear wheel 57 on the shaft 15 which meshes with a pinion 58 on a stub shaft 59 carried by a bracket 59^a. The pinion 58 is rigidly connected to a gear wheel 60 which in turn meshes with a long pinion 61 on the spindle shaft 55. The gear wheel 57 is provided with teeth throughout a part only of its periphery, the remainder of its periphery being smooth or untoothed. When the toothed portion of this gear wheel engages the pinion 58 the latter, together with the gears 60, 61 and shaft 55, will be rotated. When the untoothed portion of gear wheel 57 is adjacent the pinion 58, the latter will

120

125

130

not be rotated. At such time the pinion 58 is locked against rotation. To accomplish this, the pinion is provided on one side with a laterally projecting portion 58^a, one edge of which is formed with a concave curvature 58^b corresponding to the curvature of the outer edge of the gear wheel 57. The gear wheel 57 is also provided on one side with a laterally projecting portion 57^a, the edge of which at 57^b is convexly curved to fit the concave curvature 58^b on the pinion 58. The curved edges 58^b and 57^b thus cooperate to lock the pinion 58 against rotation when the teeth on the gear wheel 57 are not in mesh with the teeth on the pinion 58.

It will be understood that each time the shaft 55 and spindle 56 are rotated the amount of rotation is sufficient to wind the sheet or blank several times around the spindle and as the blank is provided on one side with adhesive as previously noted, the result will be the formation of a tube T on the spindle as illustrated in dotted lines in Figure 5.

In order to insure that the paper shall be wound tight about the spindle 56 and pressed down against the same, there is provided a wiper or presser 70 which is connected to a bent arm 71 pivotally connected at 72 to a bell crank lever 73 pivotally mounted at 74 on the table 10. A cam 75 on the shaft 15 is adapted to bear against a roller on the bell crank lever 73 and thereby tilt the same and move the bent arm 71. When the high portion of the cam 75 is operating against the lever 73, the arm 71 and wiper 70 will be moved so that the latter will be out of engagement with the spindle 56. When the low part of the cam 75 is effective, the lever 73 is drawn down by means of a coiled spring 76 anchored thereto and to the table 10, with the result that the wiper 70 is moved into position adjacent the spindle 56, in which position it bears against the paper being wound upon the spindle and wipes or smooths down the same so as to insure the proper formation of the tube. The bent lever 71 is made slightly yieldable by means of a spring 71^a interposed between the same and one arm of the bell crank 73. The completed tube is of the character illustrated at T in Figures 15 and 16.

The bag feeding and inserting mechanism.

After a tube is formed as previously described, a bag B of explosive material, as illustrated in Figure 16, is inserted in the tube while the same remains in position in the machine and before it is ejected therefrom. To accomplish this result, the machine is provided with an endless carrier 80 which is made up of a plurality of rectangular blocks 81 connected by sprocket links 82, the links being pivotally connected to the blocks. The carrier 80 is operated by means

of a pair of sprocket wheels 83 around which it passes, the other end of the carrier passing around a similar pair of sprocket wheels (not shown). The sprocket wheels 83 are mounted on a short shaft 83^a supported in any suitable manner on the table 10 and a ratchet wheel 84 is rigidly connected to the shaft 83^a. This ratchet wheel is engaged by a ratchet tooth 85 carried by a bell crank lever 86 pivoted at 87 on the table 10, the end of this lever being arranged to bear against a cam 88 secured to the shaft 13. By means of this mechanism the endless carrier 80 is given a step by step motion.

Each of the blocks 81 of the endless carrier is provided with a rectangular pocket or slot 81^a which extends therethrough from the top to the bottom of the block, the tops of these pockets preferably being flared as illustrated at 81^b particularly in Figures 4 and 12.

The pockets 81^a are intended to receive the bags B of explosive material, illustrated in Figure 16, and the bags may be deposited in these pockets by hand or in any other manner desired. As the bags are deposited in the pockets of the carrier, they are, of course, moved along with the carrier.

Arranged beneath the upper portion of the carrier 80 is a tubular magazine 89 which is mounted in a block 89^a supported on a standard 89^b on the table 10. The magazine 89 is provided on its upper side with a slot or opening 89^c, and the end thereof adjacent the spindle 56 is slightly tapered as shown at 89^d for a purpose later described. The magazine 89 is so arranged that as the carrier 80 is moved over the same, the pockets in blocks 81 will successively come to rest directly above this opening. In other words, as the endless carrier is moved step by step in the manner previously described, one of the pockets in blocks 81 will lie above the opening in the magazine 89 whenever the carrier is at rest.

To force the bags of explosive material from the carrier 80 into the magazine 89, there is provided a main plunger 90 and an auxiliary plunger 91. These plungers are arranged to slide up and down in suitable guides 92 secured to the table 10 and the same are carried at the end of a rocking arm or lever 93 pivoted at 94 to a standard 95 on the table. The lever 93 is operated by means of a cam groove 96^a formed in the face of a cam wheel 96 secured to the shaft 11, the lever being provided with a suitable roller 93^a engaging the cam groove. It is evident that when the lever 93 is operated the plungers 90 and 91 will be caused to move downwardly through the pockets 81^a of the endless carrier 80. The plunger 90 is of sufficient length to force a bag of explosive material from the pocket 81^a into the tubular magazine 89. The auxiliary plunger 130

91 serves the purpose of partially forcing the bags of explosive material through the pockets 81^a. It is, of course, to be understood that the plungers 90 and 91 are operated in timed relation with the step by step movements of the carrier 80 so that the plungers are caused to move downwardly during the intervals that the carrier is at rest.

10. Normally the tubular magazine 89 occupies a position slightly removed from the position occupied by a tube T which is formed on the spindle 56. Preparatory to forcing the bag of explosive material into the tube T, it is desirable to move the magazine against or into close proximity to the tube. To accomplish this result, the block 89^a of the magazine is slidably mounted on the standard 89^b and is operated so as to move a slight distance into contact with the tube T on the spindle 56 after such tube is formed and just before the bag is forced from the magazine 89. Such movement of the magazine is effected by means of a cam 100 secured to the shaft 15 and arranged to contact with the end of a bell crank lever 101 pivoted at 102 and the end of which engages a bearing plate 103 secured to the block 89^a. The cam 100 is made with a very slight throw so that the movement of the magazine 89 will be very slight, only a fraction of an inch being sufficient to enable the tubular magazine to be brought into contact with the tube on the spindle.

35. The magazine 89 is arranged substantially in axial alignment with the spindle 56 and, as above noted, the end of the magazine is made slightly tapered as indicated at 89^c. Such tapered portion is adapted to project a slight distance into the tube T which assists in supporting the tube after the spindle 56 is withdrawn, as hereafter described.

40. To force the bags from the magazine 89, there is provided a plunger 105 which is adapted to move axially through said tubular member. This plunger is slidably mounted in a standard 106 supported on the table 10 and the same is operated by means of a lever 107 pivotally mounted at 108 on the table 10. The lever 107 has at one end a forked portion 107^a which engages a pin on the plunger 105 and at its opposite end this lever engages a cam 109 secured to the shaft 13. From this it will be understood that rotation of the shaft 13 will cause the plunger 105 to move axially through the tubular magazine 89 to force a bag of explosive material therefrom into a tube T and it is, of course, to be understood that the parts are so timed that the plunger 105 will be caused to operate in proper timed relation with the other parts of the mechanism.

45. Before the bag of explosive material can be forced into the tube T, it is, of course,

necessary that the spindle 56 be withdrawn therefrom. Such movement of the spindle 56 is effected through the medium of a cam groove 110 formed in the face of the cam disk 96, this groove being engaged by a roller 111 on a rocking arm 112 pivoted on the table 10, the arm 112 also carrying a second roller 113 which is arranged between two flanges or collars 114 on the shaft 55. As the cam wheel 96 is rotated it is therefore evident that the spindle shaft 55 and spindle 56 will be caused to move to the right (Figure 5) at certain times and the mechanism is, of course, so timed that this retroactive movement of the spindle will take place just prior to or substantially simultaneously with the advance of the magazine 89 and the plunger 105 to force the bag of explosive material into the newly formed tube T. As the spindle 56 finishes rotation and is withdrawn, the tube T abuts against the stripper block 56^b to strip the same from the spindle. The long pinion 61 on the shaft 55 permits constant engagement between such pinion and the gear wheel 60 regardless of the axial movement of the shaft 55.

To insure that the tube T will be ejected or knocked out of position after the bag of explosive material is inserted therein, there is provided an ejector 115 which is normally positioned above the spindle 56 and which is operated by means of a lever 116 pivoted at 117 to an arm on the table 10, the intermediate portion of this lever being provided with a member 118 which cooperates with a cam 119 secured to the shaft 15. A spring 120 tends to draw the lever 116 downwardly and the cam 119 is provided with a low portion which permits such downward movement when this portion comes beneath the bearing member 118. The cam 119 is so shaped that the arm 116 is caused to move down quickly and the ejector 115 thus acts to eject the completed firecracker from the machine.

50. After one firecracker is ejected, the spindle 56 again advances and as it does so the next blank or sheet is in the position shown in Figure 13 and the end thereof is engaged by the slot 56^a of the spindle. The spindle is again given rotation to wind a new tube and the various operations are thus repeated in proper sequence and timed relation.

55. It is obvious that the details of the mechanism may be varied to a large extent and the invention is not to be understood as limited to the particular arrangements shown and described except as required in the appended claims.

Having thus described the invention what is claimed as new and desired to be secured by Letters Patent is:

60. 1. A machine for making firecrackers of the type having a bag of explosive material arranged in a tube, comprising a magazine

70

120

125

130

for receiving a bag of explosive material, means for holding a tube adjacent one end of the magazine, and means for forcing the bag from the magazine into the tube.

5. 2. A machine for making firecrackers of the type having a bag of explosive material arranged in a tube, comprising a magazine for receiving a bag of explosive material, means for moving the magazine against the 10 end of a tube into which the bag is to be inserted, and a plunger movable through said magazine for forcing the bag into the tube.

10. 3. A machine for making firecrackers of the type having a bag of explosive material arranged in a tube, comprising a magazine for receiving a bag of explosive material, means for holding a tube adjacent one end of the magazine, means for feeding bags of explosive material one at a time into said 20 magazine, and a plunger for forcing the bag from the magazine into the tube.

4. A machine for making firecrackers of the type having a bag of explosive material arranged in a tube, comprising a magazine 30 for receiving a bag of explosive material, a movable carrier for receiving bags of such material, means for forcing the bags one at a time from the carrier into said magazine, and a movable plunger for forcing the bags 35 one at a time from the magazine into the tubes.

5. A machine for making firecrackers of the type having a bag of explosive material arranged in a tube, comprising a tubular 35 magazine having an opening on one side through which a bag of explosive material may be inserted into the magazine, means for forcing a bag of said material through said opening, means for moving said magazine against a tube into which the bag is to 40 be inserted, and a plunger for forcing the bag from the magazine into the tube.

6. A machine for making firecrackers of the type having a bag of explosive material arranged in a tube, comprising an endless carrier for receiving bags of explosive material, a magazine associated therewith, a plunger for forcing the bags one at a time from said carrier into said magazine, means for holding a tube adjacent said magazine and a second plunger operating through said magazine for forcing the bags therefrom into the tube.

7. A machine for making firecrackers of the type having a bag of explosive material arranged in a tube, comprising an endless carrier, means for moving the same intermittently, means on said carrier for supporting bags of explosive material, a magazine, a plunger operating intermittently for forcing the bags one at a time from said carrier into the magazine, and a second plunger operating intermittently to force the bags from said magazine into the tubes.

8. A machine for making firecrackers of

the type having a bag of explosive material arranged in a tube, comprising an endless carrier having a plurality of pockets therein for receiving bags of explosive material, a magazine for receiving said bags one at a time from said carrier, a plunger for forcing the bags from said pockets into said magazine, and a second plunger for forcing the bags from said magazine. 70

9. A machine for making firecrackers of the type having a bag of explosive material arranged in a tube, comprising an endless carrier formed of a plurality of separate members, each member having a pocket extending therethrough from the top to the 80 bottom thereof, adapted to receive bags of explosive material, a magazine arranged beneath a part of said carrier, a plunger adapted to pass downwardly through said pockets to force the bags therefrom into said magazine, a second plunger operating through said magazine to force the bags therefrom, and means for intermittently operating said carrier and plungers in timed relation. 85

10. A machine for making firecrackers of the type having a bag of explosive material arranged in a tube, comprising an endless carrier having therein a plurality of spaced pockets adapted to receive bags of explosive material, a magazine arranged adjacent said carrier, a plunger movable toward and from said magazine through said pockets for forcing the bags therefrom into said magazine, an auxiliary plunger adapted to force the bags part way through said pockets, and a plunger operating through said magazine for forcing the bags therefrom. 100

11. A machine for making firecrackers of the type having a bag of explosive material arranged in a tube, means for producing a tube from a sheet of paper and including a spindle on which the tube is formed, a tubular magazine arranged in axial alignment with said spindle, means for forcing a bag 110 of explosive material from said magazine into the tube on said spindle and means for withdrawing the spindle from the tube.

12. A machine for making firecrackers of the type having a bag of explosive material arranged in a tube, a rotating spindle for forming a tube thereon, a tubular magazine arranged in alignment with said spindle, means for forcing a bag laterally into said magazine, a plunger operating through said 120 magazine to force the bag into the tube formed on the spindle and means for withdrawing the spindle axially from the tube to permit the bag to be inserted therein.

13. A machine for making firecrackers of the type having a bag of explosive material arranged in a tube, comprising a rotating spindle and means associated therewith by which a tube may be formed on the spindle, a hollow magazine arranged in axial align- 130

- ment with said spindle and having one end thereof positioned adjacent the spindle, means for supplying bags of explosive material one at a time to said magazine, a plunger operating through said magazine to force a bag therefrom into the tube formed on the spindle, and means for withdrawing the spindle axially from the tube to permit insertion of the bag therein.
- 10 14. A machine for making firecrackers of the type having a bag of explosive material arranged in a tube, a spindle, means for cutting a sheet of paper and feeding the same to said spindle, means for rotating the spindle to wrap the sheet around the same to form a tube thereon, a tubular magazine arranged in axial alignment with said spindle and adapted to receive a bag of explosive material, means for moving said magazine into contact with the tube formed on the spindle, means for withdrawing the spindle axially from the tube, and a plunger for forcing a bag axially from the magazine into the tube.
- 15 15. A machine for making firecrackers of the type having a bag of explosive material arranged in a tube, comprising a tube forming spindle, a tubular magazine arranged in axial alignment with said spindle, a plunger for forcing a bag of explosive material into said magazine, means for moving said magazine against the tube formed on the spindle, means for withdrawing the spindle axially from the tube and a plunger operating axially through said magazine to force the bag therefrom into the tube.
- 20 16. A machine for making firecrackers of the type having a bag of explosive material arranged in a tube, comprising a spindle, means for supplying a sheet of paper thereto, means for rotating the spindle to wrap said sheet around the same to form a tube, a magazine arranged in axial alignment with said spindle, means for moving the end of said magazine against the tube on the spindle to hold the tube, means to withdraw the spindle from the tube, and means for forcing a bag of explosive material from the magazine into the tube.
- 25 17. A machine for making firecrackers of the type having a bag of explosive material arranged in a tube, comprising an endless carrier formed of a plurality of connected members each provided with a pocket extending therethrough adapted to receive a bag of explosive material, means for giving said carrier a step by step motion, a magazine over which said carrier is adapted to pass, a plunger associated with said carrier, means to move said plunger into each pocket of said carrier to force the bag therefrom into said magazine, means for holding a tube adjacent the end of and in alignment with said magazine, and a plunger movable into said magazine to force the bag therefrom into said tube.
- 30 18. In a machine of the kind described, a table over which paper is adapted to be fed in a continuous strip, a spindle arranged below and at one side of said table, a platform associated with the spindle, means for feeding a strip of paper over said table, means for severing blanks or sheets from said strip and depositing the same on said platform, and means for moving said platform downwardly and laterally to successively present the blanks or sheets to said spindle.
- 35 19. In a machine of the kind described, a spindle for forming a tube, a magazine for receiving a bag of explosive material, means for retracting the spindle from the tube, and means for forcing the bag from the magazine into the formed tube.
- 40 20. In a machine of the kind described, an endless carrier having a plurality of blocks thereon, each block having a pocket extending therethrough adapted to hold a bag of explosive material, means for giving said carrier a step by step motion, a plunger movable transversely of said carrier through said pockets, means for operating said plunger in timed relation with the movements of said carrier, a magazine below said carrier and having an opening through which a bag of explosive material may be forced by said plunger, and a second plunger movable through said magazine to force the bags of explosive material therefrom.
- 45 In testimony whereof I hereunto affix my signature.

JOSEF B. DECKER.
